UNITED STATES PATENT OFFICE.

ALICE G. COOPER, OF SAN DIEGO, CALIFORNIA.

SEWING-MACHINE HEAD.

1,087,216.

Specification of Letters Patent. Patented Feb. 17, 1914.

Application filed March 13, 1912. Serial No. 683,428.

To all whom it may concern:

Be it known that I, ALICE G. COOPER, a citizen of the United States, and a resident of San Diego, in the county of San Diego and State of California, have invented certain new and useful Improvements in Sewing-Machine Heads, of which the following is a specification.

My invention relates to a scale or guide on the top surface of the bed plate of a sewing machine head, and the objects of my invention, are, to provide a scale readily visible to the operator of a sewing machine, to gage the distance of the seam from the edge of the cloth or the width of hems and the like, and to provide a means to facilitate a uniformity in seams and the like and further to provide a ready means for measuring the width thereof.

With these and other objects in view as will appear, my invention consists in certain novel features of construction, combination and arrangement of parts as will be herein-after described in detail and particularly set forth in the appended claim, reference being had to the accompanying drawings and to the characters of reference thereon, which form a part of this specification, in which:—

Figure 1 is a perspective view of a sewing machine head, showing my preferred construction, Fig. 2 is a similar view of the same showing a scale placed on a sewing machine head in a modified form from that shown in Fig. 1, and Fig. 3 is a perspective view of the scale plate.

Similar characters of reference refer to similar parts throughout the several views.

In the drawings, numeral 1 represents the bed plate of the sewing machine head, 2 the arm, 3 the needle plate, 4 the front slide, 5 the back slide and 6 the scale plate.

The sewing machine head is of the ordinary type, except that the needle plate 3 is provided with a scale starting at the needle hole therein and the inner ends of the slides

4 and 5 are provided with a continuation of said scale. Inserted in the bed plate 1 is my scale plate 6 which is preferably set into the bed plate 1, and it is provided on its upper surface with a continuation of the scale upon 50 the slides 4 and 5.

In my modified construction, instead of inserting a plate 6 for the scale, the scale is simply placed directly on the upper surface of the bed plate, continuing the scale on the 55 slides 4 and 5.

Though I have shown and described particular methods of placing a scale on sewing machine heads, I do not wish to be limited to this particular construction, but desire to 60 include in the purview of my invention, the placing of a scale, starting at the needle hole in the needle plate and extending some distance toward the arm connection, substantially as set forth in the appended claim. 65

It will be readily seen that with this scale, the determining and maintaining of the width and uniformity of seams, hems and the like will be greatly facilitated.

Having thus described my invention, what 70 I claim as new and desire to secure by Letters Patent is:—

In a sewing machine the combination of a needle plate, provided with a scale starting at the needle hole therein and extending to 75 the outer edge longitudinally with the bed plate of the machine, front and rear slides contiguous to said needle plate provided with a continuation of said scale on their inner ends and a plate detachably mounted 80 longitudinally with the bed plate of the machine provided with a continuation of said scale upon said slide.

In testimony whereof, I have hereunto subscribed my name in the presence of two 85 subscribing witnesses.

ALICE G. COOPER.
